UNITED STATES PATENT OFFICE.

VALENTINE SCHILDWACHTER, OF PEORIA, ILLINOIS.

DOOR OPENING AND CLOSING DEVICE.

1,354,135.

Specification of Letters Patent. Patented Sept. 28, 1920.

Application filed February 27, 1919. Serial No. 279,477.

To all whom it may concern:

Be it known that I, VALENTINE SCHILDWACHTER, a citizen of the United States, residing at Peoria, in the county of Peoria 5 and State of Illinois, have invented certain new and useful Improvements in Door Opening and Closing Devices; and I do hereby declare that the following is a full, clear, and exact description of the invention, which will enable others skilled in the art to which it appertains to make and use the same.

This invention relates to mechanism for opening and closing the double doors of 15 garages, fire stations and other buildings where a door opener can be used to advantage.

The main object is to provide a mechanism including a power element by which, 20 when set in motion, the double doors can be opened or closed quickly and positively.

Another object is to provide a mechanism for a door opener which when set in motion 25 will automatically move the doors to the opened or closed position and automatically stop when either of such positions is reached.

The invention includes certain details of 30 construction and arrangement of parts as will be clearly set forth in the specification and the appended drawings showing one embodiment, it being understood that changes may be made without departing 35 from the spirit and intent of the invention.

Figure 1 is a plan of the wall and double hinged doors of a building showing my invention connected therewith.

Figs. 1^a and 1^b are modifications of the 40 same.

Fig. 2 is a vertical section of a wall and part of a door showing part of the invention in connection therewith, this figure being produced on a larger scale than Fig. 1.

Fig. 3 is a transverse section of a pipe 45 and certain other parts entering into the invention.

Fig. 4 is a rear elevation of part of an operating mechanism.

Fig. 5 is a side elevation of the operating 50 mechanism, and

Fig. 6 is a plan of the same.

The invention includes a structure disposed above the doors to be operated and extending perpendicular to the plane of the 55 wall in which the doors are placed. Such structure has a movable part operatively

connected to the doors and moved by power such as an electric motor, for example, the latter being chosen since electric circuits are quite common to nearly all locations 60 whether of the cities or of the rural districts.

1 indicates one of the walls of the building and 2 double doors adapted to swing either inwardly or outwardly. In the present instance they are shown swinging inwardly. 3 is a pipe suitably supported above the meeting place of the doors, and mainly within the building but extending partially outside the same. It is slotted 70 throughout its length on its lower side at 4, Figs. 2 and 3, and slideable within it is a rod or pipe 5. At one end the said rod or pipe has a depending pin or stud 6 to which is loosely attached a pair of arms 7 whose 75 other ends are separately pivoted to one of the doors 2 by means of extended braces or brackets 8, for example, Fig. 1.

The opposite end of the rod or pipe 5 has a similar depending stud 8' to which is 80 loosely attached one end of a pitman 9 which, in turn, is attached to a crank-arm 10 carried in a suitable vertically disposed bearing 11 mounted on a support 12 on which one end of the pipe 3 may be supported, Fig. 5.

The crank-arm is adapted to rotate in said bearing and is adapted to impart longitudinal movement to the rod or pipe 5 within the pipe 3. Said crank-arm is of a 90 length, between centers, substantially equal to the distance the rod or pipe 5 is to travel to fully open or close the doors, the path of movement of the connected ends of the crank-arm and pitman being shown at the 95 dotted circle a, Fig. 1. The shaft of the crank-arm has affixed thereto a worm-wheel 13 and a shaft 14 extending vertically from the latter has a bearing in any suitable support 15 for firmly holding the said worm-wheel during operation.

16 is a pair of spaced members mounted on the support 12 for example, in which a shaft 17 of a worm 18 has its bearings, the worm adapted to have driving engagement 105 with the worm-wheel. Said shaft carries a pinion-gear 19' in mesh with a gear 20 on the worm-shaft 17, and a pulley 21 is belted to the pulley of a motor 22, Fig. 1. 23 is an electric switch of the "knife" type, for convenience, suitably mounted, and 24 is a lever to which the knife of the switch is attached.

Said lever is suitably mounted on a standard 25 for example. One arm of the lever carries a wheel or roller 25' beneath which a track 26 is adapted to rotate with the worm-wheel. As shown in Fig. 6 the track is separated into two parts or halves spaced at their ends. 27 indicates the leads of an electric circuit with which the motor 22 and the switch 23 are connected in any usual way.

28 is a shaft suitably journaled vertically in the support 12, for example, the same having an arm 29 connected by a link 30 with the said lever 24. Said shaft has an arm 31 with which a wire or cable 32 may be connected extending outside the doors in convenient reach. By pulling upon the same, the lever 24, which is normally in its "off" position, its roller lying between the track portions, with the switch open, is moved to close the latter and start the motor to rotate the crank-arm. If the doors are closed the point of connection of the crank-arm and pitman will lie at substantially the point X, Fig. 1. Now, as the 25 crank-arm moves around to the opposite position, the roller being supported on the track, the pipe or rod 5 will be drawn through the pipe 3 opening the doors to the position shown in broken lines in said Fig. 30 1. As the crank-arm and rod 5 complete their travel one of the spaces between the track portions will pass beneath the roller 25' letting that member down by gravity together with the lever 24 opening the 35 motor-circuit. Gravity is sufficient to accomplish the latter result although if desired means may be provided for assisting the movement.

To close the doors the switch may be again 40 closed from a position within the building, or outside the same by the means described, whereupon the action is repeated, the movement being automatically terminated in the manner explained.

45 In order that the motor may have time to get into full rotation before actual work or load is placed upon it provision is made for a lost-motion action. That is to say, the shaft 17 is permitted to have considerable 50 "end shake" in its bearings 16. 33 is a cross-head secured on the shaft, being preferably a flat spring-like or flexible member. 34 is an arm pivotally mounted at one end on the support 12, for instance, and 35 is a rod 55 connecting it with the arm 24. Now, as the crank-arm 10 approaches the end of its travel in closing or opening the doors, and the lever 24 breaks the circuit by opening the switch as explained, the said arm 34 is 60 pushed forward into the path of said cross-head 33, Fig. 5. As the latter in its rotation strikes the arm, the motor circuit being open, it is caused to rebound turning the worm slightly in a direction opposite that 65 which drives the worm-wheel. The rebound

due to the flexibility of the cross-head removes the friction existing between the worm and worm-wheel. The pitman and crank-arm which have been in motion up to the instant of the opening of the motor-circuit, naturally swing, by their momentum, past the center and in so doing the worm-wheel through the worm shifts the shaft 17 in its bearings to a position where, when the motor is again placed in operation, the worm can rotate several turns before power is applied to the worm-wheel thus giving the motor perfectly free action until its full speed is attained before the load is placed upon it.

80 Particularly where the motor is of the induction type it must have its full speed before the load is taken on.

The lost motion effect is obtained at the end of each closing or opening movement of the door, or at each one-half rotation of 85 said crank-arm.

As the switch 23 is closed by moving the arm 24, the arm 34 is removed from the path of the cross-head 33 automatically so as not 90 to interfere with the further rotation of the parts.

The shaft 28 as shown in Fig. 6 extends below the support 12 so that it may be readily reached and operated. The doors may 95 thus be opened or closed from within the building as well as from any distant point outside the same.

Any type of power may be employed and 100 other ways of applying it may be resorted to, all being within the meaning of the invention and its claims.

The modification of the structure, shown in Figs. 1^a and 1^b, admits of opening one of the doors 2 wider than the other when occasion demands. That is to say, it is often desirable to open one door wider than the other in garages where cars are to be driven into close quarters or when some particular placing of the car is wanted. In order to 110 provide for this a cross member *b* is rigidly secured to the rod or pipe 5, as shown in Fig. 1^b, to which a second member *c* is attached which may be shifted endwise thereon. As may be seen in this figure said member *c* extends a greater distance from the 115 said rod or pipe 5 at one side than the other. Thereby, as clearly shown in Fig. 1^a, the door connected with the longer extension through the arm 7 must be moved a greater 120 distance but at the same time both doors will be closed together as before as shown in broken lines in the figure last named.

The arms 7 may, of course, be directly attached to the member *b* instead of to the pin 125 or stud 6. Either door may be swung wider than the other by a longitudinal adjustment of the member *c*.

I claim:

1. In combination with a door, an appara- 130

tus for opening and closing the same including a rigid member extending perpendicularly to the plane of the closed door, a guide to direct the movement of the member, an 5 arm pivoted at one end to the member and at its other end to the door, a crank-arm operatively connected to the member adapted in the movement thereof to open or close the door, an electric motor adapted to be set in 10 operation including a circuit-breaker, a lever-arm in control of the latter, gearing interposed between the motor and the crank-arm, and a track portion rotatable with the gearing adapted to hold the circuit-breaker 15 closed through said lever-arm and also adapted to cause the circuit-breaker to be opened at a predetermined period in the movement of the crank-arm.

2. In combination with a door, an apparatus for opening and closing the same adapted to be set in motion and including gearing adapted to automatically terminate motion when the door has been opened or closed, power means including with said gearing a 25 worm and worm-wheel, the worm adapted to have an appreciable endwise movement whereby the driving power applied thereto is permitted to attain full movement before the worm is engaged by it to operate the 30 door operating parts.

3. Door opening and closing mechanism including in its construction a member to operate a door, a crank-arm connected thereto, a worm-wheel carrying said crank-arm, 35 a power operated worm engaging the worm-wheel, a lost motion device including an arm rotatable with said worm, and a stop adapted to be brought into the path of the arm at a termination of rotation of the worm 40 whereby the latter is made to take endwise movement with respect to said worm-wheel.

4. In combination with a door, operating mechanism therefor including a member 45 adapted for movement in a direction perpendicular to the plane of the closed door, an arm pivotally connected at its ends to the door and said member, a worm-wheel having a crank-arm, a pitman connecting the 50 crank-arm and the said member, a worm, a

power member for driving it, said worm engaging the worm-wheel, a cam track rotated by said worm-wheel and separated at diametrically opposite positions into two parts to form a recess at each said position, a device 55 for controlling the power member, a lever connected operatively to the said device and engaging the cam adapted to drop into either of said recesses, and a stop motion device comprising a part rotatable 60 with the said worm and an arm linked to the described lever and moved by it into the path of the part to suddenly terminate the rotation of said worm, the movement of the lever simultaneously moving the device having 65 control of the power member to terminate the driving relation thereof.

5. In combination with a door, operating mechanism therefor including a member adapted for movement in a direction perpendicular to the plane of the closed door, an arm pivotally connected at its ends to the door and said member, a worm-wheel having a crank-arm, a pitman connecting the crank-arm and the said member, a worm, 70 a power member for driving it, said worm engaging the worm-wheel, the worm arranged to have an endwise movement in its support, a cam track rotated by said worm-wheel and separated at diametrically opposite 75 positions into two parts to form a recess at each said position, a device for controlling the power member, a lever connected operatively to the said device and engaging the cam adapted to drop into either of said 80 recesses, and a stop motion device comprising a part rotatable with the said worm and an arm linked to the described lever and moved by it into the path of the part to suddenly terminate the rotation of said 85 worm, the movement of the lever simultaneously moving the device having control of the power member to terminate the driving relation thereof.

In testimony whereof I affix my signature 95 in presence of two witnesses.

VALENTINE SCHILDWACHTER.
